ELEVATOR OPERATING MECHANISM

Julien N. Schiff, West Englewood, N. J.

Application August 13, 1937, Serial No. 158,879

6 Claims. (Cl. 254—144)

This invention relates to elevator operating mechanisms and is directed especially to so-called sidewalk elevators adapted primarily for the transfer of freight, ashes and other materials from cellars, basements and sub-basements to the street level. Elevators of this character generally embody a platform mounted to vertically slide between fixed guides mounted in a hatch. A bow, mounted on the platform, cooperates with these guides and is provided with a curved top adapted to raise and lower hinged street level doors as the elevator is operated. The elevator is suspended on two or more cables, one end of each of which is connected to the platform and is from thence passed upwardly and over sheaves mounted in the hatch adjacent, but below, the street level and from these sheaves the cables extend downwardly and are secured to winding drums fixed on a shaft extending transversely across the bottom of the hatch at the basement level.

Under present practice the drum shaft is connected through a gear train to a winding crank which, when operated in one direction, serves to raise the elevator and, when operated in the other direction, serves to lower the same. A locking pawl is generally provided to hold the elevator in raised position, so that the hands of the operator may be removed from the handle when the elevator is at rest.

In the known mechanisms of the character described, the winding devices are bulky and take up considerable space and the elevator must be wound up as well as wound down. Furthermore, if the locking pawl and crank are both released at any one time, the elevator will drop and, if the operator is standing too close to the crank he may be struck thereby and severely injured.

The objects of the present invention are to minimize the space required for the operating parts, to appreciably economize in the cost of installation, to facilitate the operation of the elevator, and to render the installation safer than heretofore.

The present invention provides a very compact winding mechanism whereby the elevator may be raised through the operation of either a winding crank or by mechanical or electrical power, but said winding mechanism is so constituted that the elevator is automatically locked in place whenever the handle is released through the incorporation into such mechanism of a worm drive. The mechanism also embodies means for disconnecting the worm drive when it is desired to lower the elevator and there is also included an

efficient and reliable friction brake whereby the elevator may be lowered by gravity and the speed controlled by said brake.

The device of this invention materially reduces the cost of installation and renders the operation of elevators more safe and simple and less arduous than heretofore.

Features of the invention, other than those specified, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a vertical section through the hatch or shaftway at the drum shaft taken in the plane of the line 1—1 of Figure 3, but showing the shaft with the drums thereon unsectioned.

Figure 2 is a section taken in substantially the plane of the line 2—2 of Figure 1 with certain of the gears and shafts in elevation.

Figure 3 is a side elevation of the elevator operating mechanism of this invention, as it appears when viewed from the right hand side of Figure 1.

Figure 4 is a section on the line 4—4 of Figure 3.

Referring first to Figure 1 of the drawings, 1 designates the platform of the elevator guided in the conventional way for vertical movement in the hatch or shaftway 2. The platform may be provided with the usual bow, not shown, and has secured thereto lifting cables which pass about sheaves adjacent the street level in the shaftway and then extend downwardly and are secured to the drums 3 on the drum shaft 4. Any number of cables may be employed and any number of drums may be used and they may be single or double. The present invention is not limited to these factors and detailed showing thereof is considered unnecessary. The drawings simply show two lifting drums 3 of any conventional kind mounted on the drum shaft 4.

According to the present invention, I secure to the outer end of the drum shaft a large combination worm and spur gear 5, the exterior of the periphery of which is provided with worm wheel teeth 6, while the interior of such gear constitutes an internal spur gear 7. This gear may be of integral construction or may be built up if desired. The large gear 5 is keyed to the shaft 4 against rotation thereon and the shaft is mounted in bearings 4a of any appropriate type fixedly secured at the sides of the hatch.

The large gear 5 is mounted within a casing comprising a back plate 8 and a cover plate 9 secured together by bolts or anchoring studs 10. The upper part of the casing is enlarged to provide a housing 11 in which is fitted a yoke 12. This yoke is slidable toward and away from the drum shaft and extending across the fork of the yoke is a worm 13, the opposite hubs of which are journaled in the legs of the yoke and extend through slots 14 in the opposite ends of the housing 11. Thrust bearings 15 may be associated with one or both ends of the worm as desired. Secured to one end of the hub of the worm is an operating shaft 16 to which is secured a crank 15 or crank wheel 17 having an outboard bearing 18 which may be mounted on any convenient fixed support.

The top of the housing is provided with an opening 19 at the opposite sides of which are upstanding lugs 20 and a cam 21 extends between these lugs and through the opening and is adapted to bear against the top of the yoke. The cam is pivoted on a pin 22 which extends through the lugs 20 and in the cam is formed an opening 23 through which extends a pin 24 carried by upstanding lugs 25 on the yoke. The eccentric edge 26 of the opening 23 is so shaped that, when the cam is moved in a clockwise direction, the pin 24 will be elevated and lift the yoke 12 sufficiently to disengage the worm from the worm wheel teeth 6, while the exterior edge of the cam is so shaped that, when the cam is moved in a counterclockwise direction, the cam will bear down upon the yoke and force it downwardly to re-engage the worm with the worm wheel. The cam may be operated in any suitable manner, but I preferably use a link 27 connected to a hand lever 28 and employ a locking pawl 29 to lock the cam in the position wherein it holds the worm and worm gear in mesh.

Journalled in the cover plate 9 of the casing is a brake spindle 30, the outboard end of which is carried on a bracket 31. To the inner end of this spindle is fixed a pinion 32 meshing with the internal spur gear 7 and between the cover plate and the outboard bearing 31 is fixed a brake drum 33. With the brake drum cooperates the brake band 34, the opposite ends of which are secured to studs 35 carried by a lever 36 on opposite sides of the pivot 37 thereof, so that pivotal movement of the brake lever 36 will vary the braking action between the brake band 34 and the drum 33. The brake lever 35 is secured to the operating handle 38 by an interposed link 39 which may have associated therewith a locking pawl 40 of any appropriate kind.

In the operation of the apparatus the elevator is raised by rotating the hand wheel or crank 17 manually or, if desired, a suitable source of electrical or mechanical power can be connected with the shaft 16 to rotate the worm while in engagement with the worm wheel, and the power thus transmitted to the worm wheel will rotate the drum shaft 4 to raise the elevator. During this operation, the brake is of course released and the cam 21 is in the position shown in Figure 2. If the hand is removed from the hand wheel or the power shut off in any position while the cam 21 is locked in place as shown, the worm will lock the worm wheel against contrarotation. Consequently the installation will be perfectly safe as the worm wheel constitutes a self locking connection between the driving and driven parts. The elevator may be thus lifted through rotation of the shaft 16, as stated, until it reaches street

level, where it will remain locked in a perfectly safe condition until it is desired to lower the elevator. When this is desired the brake band is caused to grip the brake drum and the lever 28 is thereupon operated to act upon the cam 5 and lift the worm free of the worm wheel. This having been accomplished, the brake lever is eased up slightly to permit the brake drum to slowly rotate and allow the weight of the elevator to cause it to descend under the braking 10 action of the brake band upon the drum. It may be lowered rapidly or slowly within the will of the operator and its descent can be nicely controlled at all times for it will be noted that the brake drum is relatively large while the 15 pinion 32 is relatively small and acts upon the drum shaft 4 through the large radius of the gear 5. Consequently a very slow speed of descent for heavy loads can be readily obtained and while the elevator is descending the crank 20 handle is at rest, so that there is no danger of injury to persons such as is present in most prior installations where the crank lever is positively connected at all times to the elevator operating mechanism and must rotate irrespective of the 25 direction of the movement of the elevator.

My experience in installing elevator operating systems has shown that provision should be made for widely varying conditions of installation. Sometimes conditions require that the operating 30 mechanism be controlled from one side of the hatch while in other installations an opposite arrangement is necessary because of the space available under particular circumstances. Furthermore there are times when the operating 35 handles 17, 28, and 38 may have to be positioned relatively high and other places where they will be required to be in relatively low position. For these reasons, the parts are made so that they can be interchanged from right to left or vice 40 versa, and the cover plate 9 is also shiftable from the truly vertical position shown in full lines in Figure 3 to the right or left as indicated in dot and dash lines or dotted lines, respectively, by merely changing the particular lugs through 45 which the bolts 10 are passed. By the latter arrangement the angularity of the operating shaft 16 may be changed, so that the hand wheel or crank will be in a most convenient position and by making the parts right and left the cam 21 and its operating link 27 may be shifted over to the right side, similarly the worm and its shaft 16 may be turned end for end and the brake mechanism, with its outboard bearing bracket 31, may be also shifted over to the other 55 side of the drum shaft 4, as indicated in dotted lines in Figure 3, so that the whole structure may be controlled from the right side instead of left side, as will be clearly understood by those familiar with the practical problems of installation. 60

It will be apparent from the foregoing description that the operating parts of this invention are unusually compact which permits the device to be positioned within very confined spaces and still operate with thorough satisfaction. Moreover, by housing all of the operating parts within a closed casing, it is possible to load the casing with grease, so that these parts will operate without undue wear through long periods of time and without requiring frequent maintenance. 70 The brake drum and band are, however, in exposed position where they can be readily cooled by the surrounding air and are so accessible that they can be readily serviced when necessary without requiring dismantling of the other operating 75

parts. Moreover, the arrangement is such that the operating parts are wholly housed within a closed casing which excludes the entrance of dirt or other extraneous matter which would cause 5 wear and shorten the life of the parts.

My experience with the present invention has shown that it is thoroughly efficient in carrying out its intended purposes, that it is unusually simple to install, that it contains no parts that 10 are apt to get out of order and that it is thoroughly safe and efficient under all conditions.

The foregoing detailed description sets forth the invention in its preferred practical form, but the invention is to be understood as fully 15 commensurate with the appended claims.

Having thus fully described the invention, what I claim as new and desire to secure by Letters Patent is:

1. An elevator operating mechanism comprising 20 a lifting drum shaft, a combination worm and spur gear fixed on said shaft, a worm movable into and out of engagement with the worm wheel teeth of said gear, a pinion meshing with the spur gear teeth of said gear, means for moving the worm into and out of mesh with the worm teeth of the gear, means for rotating the worm to impart rotation to the worm gear while 25 in mesh therewith, a brake drum rigid with the pinion, and braking means associated with said drum to brake the rotary movement of the gear when the worm wheel is moved out of mesh with the worm teeth of said gear.

2. An elevator operating mechanism comprising 30 a lifting drum shaft, a combination worm and spur gear fixed on said shaft, a worm movable into and out of engagement with the worm wheel teeth of said gear, a pinion meshing with the spur gear teeth of said gear, means for moving the worm into and out of mesh with the worm 35 teeth of the gear, means for rotating the worm to impart rotation to the worm gear while in mesh therewith, a brake drum rigid with the pinion, and manually controlled braking means associated with said drum to brake the rotary 40 movement of the gear when the worm wheel is moved out of mesh with the worm teeth of said gear.

3. An elevator operating mechanism comprising 45 a lifting drum shaft, a combination worm and spur gear fixed on said shaft, a driving worm meshing with the worm teeth of said gear, a yoke carrying said worm and guided for movement toward and away from the gear to move the worm into and out of mesh with the worm 50 teeth of the gear, a cam cooperating with the yoke to move the yoke toward and away from the gear, a pinion meshing with the spur teeth of said gear, a brake drum rigid with the pinion, and braking means associated with the drum to 55 brake the rotary movement of the gear when the worm wheel is moved out of mesh therewith.

4. An elevator operating mechanism comprising 5 a lifting drum shaft, a combination worm and spur gear fixed on said shaft, a driving worm meshing with the worm teeth of said gear, a yoke carrying said worm and guided for movement toward and away from the gear to move the worm into and out of mesh with the worm teeth of the gear, a cam cooperating with the yoke to move the yoke toward and away from the gear, a pinion meshing with the spur teeth of said gear, a 10 brake drum rigid with the pinion, braking means associated with the drum to brake the rotary movement of the gear when the worm wheel is moved out of mesh therewith, manually operable means remote from the worm and connected thereto to rotate the same, manually operable means remote from the cam and connected thereto to operate the same, and manually operable means remote from the braking means and operatively connected thereto to operate the same. 15

5. An elevator operating mechanism comprising 20 a lifting drum shaft, a combination worm and spur gear fixed on said shaft, a driving worm movable into and out of engagement with the worm wheel teeth of the gear, a pinion meshing with the spur gear teeth of said gear, means for moving the worm into and out of mesh with the worm teeth of the gear, a brake drum rigid with said pinion, a brake band cooperating with said drum, and a casing enclosing the combination 25 gear and supporting the worm, pinion, brake drum and brake band in cooperative assembled relation to permit them to be handled as a unit in mounted desired angular position with respect to the axis of the lifting drum shaft. 30

6. An elevator operating mechanism comprising 35 a lifting drum shaft, a combination worm and spur gear fixed on said shaft, a driving worm movable into and out of engagement with the worm wheel teeth of the gear, a pinion meshing with the spur gear teeth of said gear, means for moving the worm into and out of mesh with the worm teeth of the gear, a brake drum rigid with said pinion, a brake band cooperating with said drum, a casing enclosing the combination gear 40 and supporting the worm, pinion, brake drum and brake band in cooperative assembled relation to permit them to be handled as a unit in mounted desired angular position with respect to the axis of the lifting drum shaft, means positioned remote from the worm and connected thereto for driving the worm, means positioned remote from the worm moving means and connected thereto for moving the worm into and out of mesh with the gear, and means positioned remote from the brake band and connected thereto for controlling the tension of the brake band about the drum. 45
